GOLF CLUB CART

Irene C. Vogt, 116 N. Walnut St., Wilmington, Ohio
Filed May 25, 1962, Ser. No. 197,701
1 Claim. (Cl. 280—47.19)

The present invention relates to golf club carts generally and in particular to a lightweight weatherproof cart for carrying golf clubs in individual compartments.

An object of the present invention is to provide a lightweight weatherproof golf cart of unique design and improved performance.

Another object of the present invention is to provide a golf cart which is readily stored, one which may be stored outside in all weather without damage thereto, one which is readily converted from the storage position to a use position, and one which is economically feasible.

A further object of the present invention is to provide a golf cart employing lightweight corrugated translucent and colorful plastic panels, one which may be produced in any color desired or in combinations of color, one which holds the golf clubs in separate compartments from which they are readily removable, and one in which each of the compartments for the golf clubs is fully ventilated thereby preventing mildew to the handles of the golf clubs.

These and other objects and advantages of the present invention will be fully apparent from the following description in which a preferred embodiment of the present invention is described and which is to be constructed in the light of the accompanying drawings, in which:

FIGURE 1 is an elevational view of the golf cart of the present invention in a position of use for rolling movement over a ground surface,

FIGURE 2 is a position of the golf club cart in a rest condition,

FIGURE 3 is an elevational view of the cart as viewed at right angles to FIGURE 2,

FIGURE 4 is a view on an enlarged scale, taken on the line 4—4 of FIGURE 3,

FIGURE 5 is a top plan view with the handle in folded condition,

FIGURE 6 is a view taken on the line 6—6 of FIGURE 4,

FIGURE 7 is a fragmentary sectional view of the assembly shown in FIGURE 4,

FIGURE 8 is a view taken on the line 8—8 of FIGURE 7,

FIGURE 9 is a view on an enlarged scale, taken on the line 9—9 of FIGURE 4, and

FIGURE 10 is a view taken on the line 10—10 of FIGURE 4.

Referring in detail to the drawings, in which like numerals indicate like parts throughout the several views, the golf club cart according to the present invention comprises a horizontally disposed axle 10 having wheels 12 and 14 on the end portions thereof.

Rising from the axle 10 is an upright body 16 fabricated of a plurality of translucent plastic corrugated sheets secured together so as to form a plurality of upright substantially circular compartments, as shown best in FIGURE 10.

Any number of sheets of plastic may be used and four are shown in the present invention and designated by the numerals 18, 20, 22, and 24. The sheets are arranged in oppositely facing directions so that their high points may be secured together by rivets 26.

A U-shaped bracket 28 has its bight secured to the sheet 24 by other rivets 30 and between the legs 32 and 34 of the bracket 28 extends another rivet 36. Pivotedly connected to the rivet 36 is an end portion of a handle

2

38. Coil springs 40 are circumposed about the portion of the rivet 36 on each side of the handle 38 between the legs 32 and 34.

As shown in FIGURE 4, the end portion of the handle 38 adjacent the rivet 36 is provided with an elongated closed slot 42 in which is slidable a pin 44. A coil spring 46 biases the pin 44 outwardly away from the rivet 36.

The legs 32 and 34 of the bracket 28 are provided with notches 48 and 50 by means of which the handle is positioned either as in FIGURE 1 or in FIGURE 2, horizontal or substantially vertical, respectively.

The other end portion of the handle 38 carries a hand grip 52 fabricated of rubber, plastic, or the like so as to provide a comfortable hand hold for the handle 38.

On the side of the body 16 opposite to the bracket 28 is a box 54 having a lid 56 extending thereover. The box 54 includes a base plate 58 secured by rivets 61 to the adjacent sheet 18.

Below the box 54 and midway of the sheet 18 is a support member 60 having one end pivotally connected by a pin 62 to a U-shaped bracket 64 for swinging movement from a position below the axle 10 to a position swung upwardly and in nested condition against the sheet 18.

The bracket 64 is secured by rivets 66 to the sheet 18, as shown most clearly in FIGURE 7.

The support member 60 is provided with a slot 68 receiving the pin 62 and with a pin 70 which is received in a notch 72 provided in the legs of the bracket 64.

A rubber or plastic cup 74 is carried on the end of the support member 60 remote from the bracket 64.

When the support member 60 is in the swung upwardly position out of use it is held between the arms 76 of a bracket 78 which is secured by rivets 80 to the sheet 18.

Interposed between the sheets 18 and 20 adjacent the lower ends thereof is a bar 82 forming a closure element for the lower end of the compartment formed by the sheets 18 and 20. Similarly positioned with respect to the sheets 20 and 22 is another bar 84 and still another bar 86 is interposed between the sheets 22 and 24 to form a closure for those sheets.

In use, as in FIGURE 1, the handle 38 is moved to the horizontal position and the pin 44 is seated in the slot 48. The support member 60 is in a nested position swung upwardly and held by the bracket 78.

Golf clubs as at 88 in FIGURE 3, are disposed with their shanks received in the spaces provided between the bowed portions of the sheets 18, 20, 22, and 24 with their free ends resting upon the adjacent bars 82, 84, or 86, as the case may be.

Preferably, the axle 10 has threaded portions on each end on which are received nuts 90 secured in place by cotter pins 92. Inwardly of the nuts 90 are washers 94 and 96 on each side of the adjacent wheel 12 or 14 and a bearing assembly 98 is formed or provided in the wheel 12 or 14 for the purpose of making the wheel as friction free as possible.

In a position of storage, the support member 60 is swung downwardly as in FIGURE 4 and the handle 38 is swung downwardly to where it is held in the downwardly swung position by means of a clip 100 secured to the sheet 24 by rivets 102.

In use, the golf club cart of the present invention will protect the handles or shanks of golf clubs and the box 54 will provide space for gloves, golf balls, golf tees, and the like.

When stored, the golf club cart of the present invention takes up little space and has three point support on the two wheels 12 and 14 and on the support member 60 in an upright condition.

While only a preferred form of the invention is shown

3

and described other forms of the invention are contemplated. The sheets of corrugated plastic may be of such colors as desired for identification purposes or may be of mixed colors as desired. Numerous changes and modifications may be made in the design of the golf club cart of the present invention for manufacturing purposes.

What is claimed is:

In a golf club cart including a wheel supported axle, an upright body rising from said axle, said body being fabricated of four vertically disposed sheets of plastic material, the first and fourth sheets each being corrugated so as to have three concave sections on one face and four concave sections on the other face, the second and third sheets each being corrugated so as to have four concave sections on one face and five concave sections on the other face, said sheets being arranged so that the four concave sections on the other face of said first sheet are in registry with the four concave sections on said one face of said second sheet, with the five concave sections on the other face of said second sheet in registry with the five concave sections on the other face of said third sheet,

and with the four concave sections on said one face of said third sheet in registry with the four concave sections on the other face of said fourth sheet, means securing adjacent ones of said sheets together, a handle pivotally connected by one end to said body intermediate the ends of said body, and a bar extending along the lower ends of each of the adjacent sheets partially closing the substantially circular compartments provided by the registering adjacent concave sections, each of the compartments being adapted to receive therein the shaft of an inverted golf club.
